UNITED STATES PATENT OFFICE.

LUCIAN W. BUGBEE AND LUCIAN W. BUGBEE, JR., OF INDIANAPOLIS, INDIANA, AS
SIGNORS, BY MESNE ASSIGNMENTS, TO CONTINENTAL OPTICAL CORPORATION, OF
NEW YORK, N. Y., A CORPORATION OF DELAWARE.

TOOL FOR TREATING OPHTHALMIC LENSES AND PROCESS OF MAKING SAME.

Original application filed December 6, 1924; Serial No. 754,343. Divided and this application filed November 24, 1925. Serial No. 71,258.

This invention consists of an improved tool for polishing or fine grinding and generating the surface of an ophthalmic lens and the process of making such tool.

5 The object of the invention is to improve as well as cheapen and simplify the production of tools for fine grinding and polishing ophthalmic lenses. This process has been invented in connection with the development of machines for generating surfaces, involving the principle of the construction set forth in an application of Lucian W. Bugbee, Serial No. 653,367, filed June 23, 1923, and this application is a division from 10 our former application for process of making lenses, Serial No. 754,343, filed December 6, 1924.

One feature of the invention consists in the process of forming the tool for fine 20 grinding or polishing ophthalmic lenses, by shaping the operative surface of such tool on the surface of the lens blank which is to be fine ground or polished. This is done by placing on the lens blank which is to be 25 ground, a sheet of lead or other flexible fine grinding or polishing material, coating the tool holder with cement and pressing the same in engagement coaxially with the layer of flexible material on the lens to be ground 30 or polished. This will cause said grinding or polishing sheet to adhere to the tool and thus shape the grinding or polishing surface thereof, which surface from the necessities of its manufacture will accurately and 35 faithfully conform to the curvature or surface of the lens blank or lens to be polished.

The full nature of the invention will be understood from the accompanying drawings and the following description and 40 claims:

In the drawings, Figure 1 is a central section through a lens block and rough ground lens blank secured thereon, and a sheet of lead placed thereon. Fig. 2 is a 45 perspective view of a tool holder coated with cement. Fig. 3 is a section through the lens block, lens, sheet of lead and cement and tool holder, all pressed together. Fig. 4 is a perspective view of the finished tool for fine grinding and polishing made by this process.

In the art of making ophthalmic lenses, particularly toric lenses, by employing the

process herein set forth, the lens 10 is rough ground while secured to a lens holder 11. 55 The blank from which the lens is ground is secured to such lens holder by reason of the face of the lens blank coming in direct contact with an annular beveled surface 12 of the lens block, and the lens block is preferably of slightly less curvature than the surface of the lens or lens blank, so that the lens blank will be slightly spaced away from the lens block in the central part thereof and the lens blank and lens are secured to the block by a small body of cement 60 13, as shown in Fig. 1. The manner of mounting the lens blank on the lens block for rough grinding, however, is relatively immaterial to this process and invention, as 65 it is applicable regardless of how the lens is secured to the lens block while being rough ground.

After the lens has been rough ground, it must be fine ground and polished, and to 75 that this process relates, and the tool produced by the process may be employed either for fine grinding or for polishing. The surface of the lens is generated and determined by the rough grinding heretofore described. 80 The fine grinding and polishing do not as a rule materially modify the generated surface of the lens and preferably should not modify it. Therefore, the tool for fine grinding or 85 polishing should have a polishing surface which conforms exactly to the lens surface to be treated. In order to produce this result in a very simple and accurate manner this process was invented.

In the first place a sheet of lead 15 or 90 other flexible abrading or polishing material is placed on the ground or previously generated surface of the lens blank and pressed tightly thereon so that it will be given a shape exactly corresponding to the lens. 95

In the next place a layer of cement 16 is spread over the face of a tool holder 17 and then the cemented face of the tool holder is brought against the sheet of lead and the lens blank and lens holder 11 coaxially and subjected to pressure so that the sheet of lead will adhere to the cement on the tool holder 17 and have an abrading or polishing surface exactly corresponding to the generated surface of the lens blank. This is 100 105 illustrated in Fig. 3. Then the fine grind-

ing or polishing tool is removed from the lens blank and lens holder, as shown in Fig. 4, said tool when thus made consisting of the tool holder 17, layer of cement 16 and the sheet of lead or other flexible material 15 secured thereto.

When the device shown in Fig. 4 is used for fine grinding, the lens holder with the lens blank thereon and the fine grinding tool are relatively rotated simultaneously according to the usual practice so as to fine grind the lens. This greatly cheapens the process of fine grinding and also insures no change whatever of the curvature of the lens from that generated by the grinding machine. This last feature is of great value.

The next step in the process of making the lens is to polish the lens and for this purpose a polishing tool is made in a manner similar to the fine grinding tool above described and shown in Fig. 4, excepting that instead of a flexible sheet of lead or like abrading material being first shaped over the lens, a sheet of felt or like flexible polishing material is merely placed on the lens blank and adhered to the tool holder in substantially the same manner as above described by bringing the cement covered face of the tool holder into engagement therewith under pressure so that the felt or like flexible polishing material will conform to the shape of the lens, so that it, during the polishing of the lens blank, will not to any extent change the curvature of the surface generated on the lens in the rough grinding operation. With this process neither the lead sheet nor the cement or pitch need be

of uniform thickness as the pressure on them of the lens blank and the tool will cause the material added to the tool to be substantially of uniform thickness and at any rate to have an operative grinding or polishing surface which conforms exactly to the curvature of the surface to be ground or polished. Also the lens blank in the process of forming this tool is brought into contact only with the sheet of lead or other flexible sheet which are not adhesive or sticky so that they will not stick to the lens blank, but on the contrary the pressure on the lead sheet of the lens blank will tend to make its surface smooth.

The invention claimed is:

The process of making a tool for treating the surface of an ophthalmic lens after such surface has been generated, which process includes placing a flexible sheet of material on the surface of the lens which is to be subsequently treated, forming the face of a tool holder with substantially the reverse curvature of the surface of the lens to be treated, covering such face of the tool holder with a layer of cement, and bringing the cement on the face of the tool holder into engagement with the sheet of material on the covered face of the lens under pressure, whereby the flexible sheet of material will adhere to the tool and have the exact shape of the surface of the lens which is to be subsequently treated.

In witness whereof, we have hereunto affixed our signatures.

LUCIAN W. BUGBEE.
